United States Patent Office

Des. 211,600
Patented July 2, 1968

211,600

DESK LAMP

Hiroshi Daito, Kyoto, Japan, assignor to Blackwell Electronics Ind., Co., Ltd., Kyoto, Japan, a corporation of Japan

Filed Apr. 14, 1967, Ser. No. 6,713

Term of patent 14 years

(Cl. D48—20)

FIGURE 1 is a perspective view of a desk lamp showing my new design;

FIGURE 2 is a front elevational view;

FIGURE 3 is a rear elevational view;

FIGURE 4 is an elevational view from one side of the lamp;

FIGURE 5 is an elevational view from the opposite side, showing the lamp collapsed; and

FIGURE 6 is a top plan view.

I claim:

The ornamental design for a desk lamp, as shown and described.
